UNITED STATES PATENT OFFICE.

PETER JOHN POELMAN, OF NEW ORLEANS, LOUISIANA, ASSIGNOR OF ONE-HALF TO CHRIS JACOB, OF SAME PLACE.

FENDER OR GUARD FOR CARS.

SPECIFICATION forming part of Letters Patent No. 610,915, dated September 20, 1898.

Application filed May 18, 1898. Serial No. 681,056. (No model.)

To all whom it may concern:

Be it known that I, PETER JOHN POELMAN, a citizen of the United States, residing at New Orleans, in the parish of Orleans and State 5 of Louisiana, have invented certain new and useful Improvements in Fenders or Guards for Cars, of which the following is a full and complete specification, such as will enable those skilled in the art to which it appertains 10 to make and use the same.

This invention relates to fenders or guards for cars; and the object thereof is to provide an improved device of this class which is designed to prevent a person or object from 15 passing under the car, and thus avoid the serious and sometimes fatal accidents which follow the striking of a person or object by a car when in motion, a further object being to provide a combined fender and brake in 20 which the brake is operated by the fender.

The invention is fully disclosed in the following specification, of which the accompanying drawings form a part, in which—

Figure 1 is a sectional side view of the bottom of a car provided with my improved fender; Fig. 2, a front end view thereof, and Fig. 3 a bottom plan view.

In the drawings forming part of this specification the separate parts of my improvement are designated by the same numerals 30 of reference in each of the views, and in said drawings I have indicated at 5 the bottom of a car, and in the practice of my invention I connect with the bottom of the car, a short 35 distance rearwardly of the front end thereof, a cross-plate 6, which is provided at each end with a downwardly-directed hanger or arm, or these arms or hangers 7 may be formed separately and secured to the car in any de- 40 sired manner, and mounted therein is a shaft 8, which is provided centrally with an upwardly-directed arm 9 and a forwardly and upwardly curved arm 10, which is provided at its front end with a downwardly-directed 45 hook 11, which passes through the eye 12 of a vertically-movable rod 13, which passes loosely through the bottom of the car and is provided at its upper end with a head 14. The shaft 8 is also provided at each end with 50 a downwardly-directed arm 15, with each of which is connected a forwardly-directed rod

16, with each of which is pivotally connected a backwardly-directed arm 17, and the arms 17 are rigidly connected with a cross-head 18, the ends of which are connected with depending arms 19, which are pivotally connected with hangers 20, secured to the bottom of the car, and the lower ends of which support a cross-rod 21.

The upwardly-directed arm 9 of the shaft 60 8 is pivotally connected with a horizontal bar 22, the rear end of which is connected with a pin 23, which is secured to the end of a horizontal sliding bar 24, mounted in a keeper 25, secured to the bottom of the car, and connected with the bottom of said keeper is an expansive spiral spring 26, the forward end of which is connected with the lower end of the pin 23, by means of which the bars 22 and 24 are connected.

Rearwardly of the keeper 23, which is arranged centrally of the bottom of the car, are two transverse plates 27 and 28, each of which is provided at its opposite end with downwardly-directed arms or hangers 29; but the 75 transverse bars or plates 27 and 28 are not absolutely essential and the arms or hangers 29 may be formed separately, if desired, and secured to the bottom of the car in any de- 80 sired manner.

Mounted in the forward downwardly-directed arms or hangers 29 is a shaft 30, which is provided centrally with an upwardly and forwardly directed arm 31, which in the normal position of the parts rests against the 85 rear end of the bar 24, as shown in Fig. 1, and secured to the opposite ends of the shaft 30 are downwardly and forwardly directed arms 32. The rear arms or hangers 29 are also provided with a shaft 33, which is mounted therein, and the ends of which are provided with downwardly and forwardly directed arms 34, rigidly secured thereto, and the arms 32 and 34 are pivotally connected at the lower ends with the sides of the fender proper, which consists of a yoke-shaped frame 95 comprising sides 35 and the forwardly-directed cross head or bar 36, and secured to the rear ends of the sides 35 in any desired manner are brakes 38, which are designed to 100 bear upon the wheels 39 of the car, and connected with the bottom of the car rearwardly

of said wheels is a hanger 40, with which is connected a contractile spring 41, the forward end of which is connected with a central arm 42, similar to the arms 34, and the rear end 5 of which is pivotally connected with the shaft 33 and the front end thereof pivotally connected with a cross-rod 43, by means of which the side arms 34 are connected with the sides 35 of the main fender. The arms 32 of the 10 shaft 30 are also connected with the sides of the main fender by a cross-rod 44, and the main fender-frame is provided with a network 45, composed of any desired material, which extends backwardly and upwardly over 15 or between the arms 32 and over or between the arms 34 and over the arm 42 and is connected with the rear shaft 33.

The main fender, as hereinbefore stated, consists of the yoke-shaped frame 35 and the 20 parts connected therewith and which are normally held in the position shown in Fig. 1, while the front depending arms 19, the cross-rod 21 at the bottom thereof, and other parts connected therewith constitute a front 25 guard by means of which the main fender or guard may be lowered adjacent to the ground and the brakes 38 thrown into operation, and the rod 21 of the forward guard may be provided with cushion-rollers, if desired, and 30 the cross-rod 18, which forms a part of said guard, may also be cushioned, so as to prevent injury to a person struck thereby when the car is in motion.

The operation will be readily understood 35 from the foregoing description when taken in connection with the accompanying drawings and the following statement thereof: Suppose the parts of the apparatus to be in the position shown in Fig. 1 and the car to 40 be in motion. If a person or object should be struck by the forward guard, the arm 9 of the shaft 8 will be forced forwardly, carrying with it the bars 22 and 24. This operation would release the arm 31 of the shaft 30, and 45 the main fender would drop downwardly, the spring 42 aiding in this operation, and the brakes 38 would be thrown in contact with the wheels 39. If the person or object should pass beneath the forward guard, said person 50 or object would be received on the main fender, which would be close to or adjacent to the ground or the rails of the track, and the passage of such person or object beneath the car would be prevented. This operation of 55 the parts of the apparatus is automatic, as will be readily understood, and is occasioned by the striking of a person or object by the forward guard. If, however, the driver or motorman should see a person or object on 60 the track and be desirous of operating the fender, as hereinbefore described, and lowering it into position, all that is necessary is to force downwardly the vertically-movable rod 13, and the operation of the various parts of 65 the apparatus will be the same as that hereinabove described when a person or object is struck by the front guard.

It will be understood that the forward part of the bottom 5 constitutes the platform of the car, on which the driver or motorman 70 stands, and my improved apparatus is simple in construction and operation and perfectly adapted to accomplish the result for which it is intended, and, if desired, when my improved fender or guard is used in connection 75 with an electric car the arrangement may be such that the dropping of the fender and the throwing of the brakes into operation will operate to disconnect the power or close the current, and thus to bring the car to a stop. 80

Having fully described my invention, I claim as new and desire to secure by Letters Patent—

1. The combination with the bottom and platform of a car, of a guard pivotally connected with the bottom of the platform and normally held in a vertical position, a shaft which forms a part of said guard, a sliding spring-operated bar mounted beneath the bottom of the car and connected with said shaft, 85 transverse shafts mounted rearwardly of the rear end of said sliding bar, one of which is provided with an arm which abuts against the end of said bar, side arms connected with said shafts, a fender-frame pivotally connected 90 with said side arms, and a spring secured to the bottom of the car rearwardly of said shafts and operating to throw the fender-frame downwardly, substantially as shown and described. 95

2. The combination with the bottom and 100 platform of a car, of a guard pivotally connected with the bottom of the platform and normally held in a vertical position, a shaft which forms a part of said guard, a sliding spring-operated bar mounted beneath the bottom of the car and connected with said shaft, 105 transverse shafts mounted rearwardly of the rear end of said sliding bar, one of which is provided with an arm which abuts against the end of said bar, side arms connected with said 110 shafts, a fender-frame pivotally connected with said side arms, and a spring secured to the bottom of the car rearwardly of said shafts and operating to throw the fender-frame downwardly, said fender-frame being also provided 115 with brakes which are adapted to operate in connection with the wheels of the car, substantially as shown and described.

3. The combination with the bottom of a car and platform thereof, of a guard pivotally supported beneath the platform and normally held in a vertical position, a transverse shaft which forms a part of said guard, a vertically-movable pin passing through the platform and connected with said shaft, a sliding 120 bar connected with an arm secured to said shaft, a supplemental bar pivotally connected with the rear end of said sliding bar, and mounted in a keeper secured to the bottom of the car, a spring for drawing said bars backwardly, transverse shafts mounted rearwardly 125 of said keeper, one of which is provided with an arm which abuts against the rear end of said supplemental bar, side arms connected 130

with said shafts, and a main fender connected with said side arms and normally held in a raised position, substantially as shown and described.

5 4. The combination with the bottom of a car and platform thereof, of a guard pivotally supported beneath the platform and normally held in a vertical position, a transverse shaft which forms a part of said guard, a vertically-movable pin passing through the platform and connected with said shaft, a sliding bar connected with an arm secured to said shaft, a supplemental bar pivotally connected with the rear end of said sliding bar, and 10 mounted in a keeper secured to the bottom of the car, a spring for drawing said bars backwardly, transverse shafts mounted rearwardly

of said keeper, one of which is provided with an arm which abuts against the rear end of said supplemental bar, side arms connected 20 with said shafts, and a main fender connected with said side arms and normally held in a raised position, said fender being provided with brakes, and a spring which operates to draw the fender downwardly, substantially 25 as shown and described.

In testimony that I claim the foregoing as my invention I have signed my name, in presence of the subscribing witnesses, this 11th day of May, 1898.

PETER JOHN POELMAN.
